(57) **CLAIM**

The ornamental design for a helmet with device element, as shown and described.

DESCRIPTION

FIG. 1 is a rear elevated perspective view of a helmet with device element, showing the new design;

FIG. 2 is a rear view thereof;

FIG. 3 is a front view thereof;

FIG. 4 is the side view thereof;

FIG. 5 is the opposite view thereof;

FIG. 6 is a bottom view thereof; and,

FIG. 7 is a top view thereof.

In all figures, any showing of the environment and/or drawing disclosure and/or vents by broken lines is for illustrative purposes only and forms no part of the claimed design.
